VENTILATING DEVICE

Grover C. Oakes, Tarentum, Pa.

Application April 9, 1934, Serial No. 719,669

11 Claims. (Cl. 296—44)

My invention relates to ventilating devices for windows and in its more specific aspect for windows of conveyances, such as automobiles, aeroplanes and other land, air or water conveyances.

It is well known that the air currents flowing along the sides of a car, due to its speed, are bent outwardly at the front corner posts and return into contact with the sides at a point intermediate the front and rear ends of the forward windows. Therefore, if an opening be provided only in the region between the front corner post and said intermediate point, no air will blow from the outside to the interior of the car through said opening but, rather, the inside air will be drawn out therethrough and draftless ventilation will result. Advantage of this phenomenon has heretofore been taken to provide for draftless ventilation, by cutting away the forward upper portion of the glass window or the forward lower portion of the top window frame member, the window when partially raised into initial contact with said member closing the window opening save for said cut away portion, through which draftless ventilation takes place. By raising the window fully the entire window opening is closed.

These expedients, while effective for ventilation, alter the lines of the car body or window structure and are costly to make since in the one case they involve forming an elongated recess in the lower side of the top frame member, materially narrowing it at that point, and in the other case cutting out a similar recess from the upper front corner of the plate glass window, an expensive operation.

My invention contemplates the provision of a similarly located ventilating opening but without the necessity of modifying either the lines of the door frame or of the window, itself, so that the external lines of the fixed parts of the car body and window remain unchanged. This I accomplish at a greatly reduced cost. Moreover, my device may be quickly, easily and cheaply applied to cars already in use without any modification of their fixed structure, whatever.

To these ends my invention contemplates the substitution for the cushioning felt, or other resilient material, in the window seat channel of the top window frame member, of a cushioning member, conveniently of U-shape in cross section, preferably of resilient material, such as rubber or the like. Where a U-shaped member is used one or both of its sides are extended a material distance below the lower edge of the top frame member, the extended side or sides being cut away at the forward end or ends, at

least to the lower edge of the top frame member, to form a ventilating opening. This member therefore serves the double function of providing a cushioning seat for the window and also an opening for draftless ventilation. The latter result is effected by raising the window to the lower edge of the U-shaped member. In this position as well as in the full raised position there is preferably a positive contact between the resilient member and the window top, preventing drafts and rattling or vibration. To further increase the anti-rattling characteristics of my device its extended side or sides may conveniently converge slightly, the inner free lower edges being drawn out to permit easy ingress of the window top.

In another aspect my invention contemplates the provision of a ventilating strip made of a material that may be easily cut and mounted in ventilating position by the layman without special tools.

A ventilating strip made of rubber or similar material that may be easily cut with ordinary tools answers this purpose. A strip made of rubber and slightly longer than the maximum length required may be easily cut off with a knife at either or both ends to adjust both the overall length and that of the ventilating opening to that most appropriate to any particular make of car. Moreover, since its base as well as its side or sides is flexible it may be easily bent into engagement with the curved bottom of the top frame member or the channel therein without cutting or trimming its base, as would be necessary in the case of glass or other rigid material. To facilitate mounting, its base may be further covered with an adhesive of appropriate character, covered by a protective fabric, which can be peeled off when ready for use. After cutting to length, the width of frame channels being substantially uniform in all makes of cars, when the U-shaped type of strip is employed it is only necessary to remove the protecting fabric and mount the strip by means of its channel on the top of the glass window in its lowered position. Then by simply raising the window to its extreme upward position the strip will be forced into place, the adhesive securing it in the channel of the top frame member. It is therefore obvious that no special skill or labor on the part of the user will be required to mount the strips and both front windows can be equipped in a few minutes.

Other novel features and advantages of my invention will hereinafter appear.

In the accompanying drawing showing for purpose of exemplification but without limiting my

invention or claims thereto, certain practical embodiments of the principles of my invention:

Fig. 1 is a side elevation of a portion of a car showing my ventilating strip installed therein.

5 Fig. 2 is a vertical section on the line 2—2 of Fig. 1.

Fig. 3 is a horizontal section on the line 3—3 of Fig. 1.

10 Fig. 4 is a perspective view of my ventilating strip with a portion of the adhesive protecting fabric separated at one end, and

Fig. 5 is a vertical section of one of the possible modifications of my invention.

Referring to the drawing, there is shown a car body 1 provided with side door 2 having side frame members 3 and top window frame member 4, with window channel 5 in its bottom. In this channel my ventilating strip 6 is conveniently mounted. This strip is shown in Figs. 1—4 as provided with a base 7, two side extensions 8, cut away at their forward ends 9 to provide a ventilating opening, the front side portions 10 being only deep enough to serve as cushioning means for the window when fully raised. It is obvious that

25 26 when made of rubber or similar flexible material the base 7, and particularly that portion of it under the shallow sides 10 where the curvature of window top frame channels is greatest, will readily bend into engagement with said channels 30 without the necessity of trimming to a fit. In order to install it is only necessary to cut to length and remove the protecting fabric 11 from the adhesive 12 and mount the strip in the top frame channel in the manner already described.

35 Of course any other manner of mounting the strip may be employed.

In Fig. 5 the ventilating device is shown as having only one side extended downwardly to effect ventilation the other side 8' being only of sufficient depth to effect cushioning of the channel in top frame member 4. This and other forms may where found desirable be reinforced by a flexible plate 13 such as thin sheet steel, this being conveniently omitted from the cut away portion 9 45 to permit easier bending of the forward end of base 7.

The side extensions 8 are preferably designed to positively contact the glass window 14 both when the latter is in draftless ventilating position and when in fully closed position, said extensions preferably being beveled as at 15 to facilitate the entry of the glass between or its movement past said extensions. To this end the extensions may be slightly inclined towards the 50 glass or provided with inwardly extending horizontal ribs or projections 16. By these expedients all chattering and rattling of the window is prevented.

In Fig. 3 is shown the direction of the air currents when the window is in draftless ventilating position.

It will be understood that changes may be made in the forms disclosed as where, for instance, the door is not provided with an upper window frame but the window when raised has a seat in the top. Here a single cushioning extension located on the inner side of the window and suitably secured to the seat may be employed. Such changes do not depart from the spirit of my invention. It is also obvious that certain features may sometimes be used to advantage without a corresponding use of other features.

I claim:

1. In a ventilating system for conveyances, in combination: a conveyance provided with a slid-

ing window; a channeled top frame member for receiving the upper edge of said window when raised; a cushioning means in said first mentioned channel extending downwardly a substantial distance below said top frame member and into contact with the window when raised to seal against influx of air and to prevent rattling, said means being cut away at its forward end to form a ventilating opening into the interior of the conveyance when the window is raised substantially to the lower edge of said channeled cushioning means.

2. In a ventilating system for conveyances, in combination: a conveyance provided with a sliding window; a seat for receiving the upper edge 15 of the window when raised; cushioning means secured to said seat and extending a substantial distance below the same and into contact with the window when raised to seal against influx of air and to prevent rattling, said means being cut 20 away at its forward end to form a ventilating opening into the interior of the conveyance when the window is raised substantially to the lower edge of said cushioning means.

3. A combined cushioning and ventilating device 25 adapted to replace the conventional cushioning means employed in the channeled top frame member of window guideways for vehicles, comprising an elongated member of resilient material, U-shaped in cross section, and having at 30 least one of its legs dimensioned to extend a substantial distance below said top frame member when said device is inserted in the channel of the latter and into contact with the window when raised to seal against influx of air and to prevent rattling, said extended leg or legs being cut away at the forward end to form a ventilating opening when the window is raised substantially to the lower edge of said device.

4. A cushioning and ventilating device adapted 40 to replace the conventional cushioning means employed in the stationary seat provided in vehicles to support the top edge of a window when raised, comprising an elongated member of resilient material adapted when mounted in position to extend a substantial distance below said seat and into contact with the window when raised to seal against influx of air and to prevent rattling, said device being cut away at its forward end to form a ventilating opening when the window is raised 50 to the lower edge thereof.

5. A cushioning and ventilating device adapted to be attached to the stationary seat provided in vehicles to support the top edge of a window when raised, comprising an elongated member 55 of severable material adapted when mounted in position to extend a substantial distance below said seat and being substantially uniform in cross-section, said device being cut away at its forward end to form a ventilating opening, said device being initially of greater length than required by the stationary seat but readily capable of being cut off at either or both ends to permit of adjusting it to a window length and simultaneously adjusting the length of the ventilating opening.

6. A cushioning and ventilating device adapted to be attached to the stationary seat provided in vehicles to support the top edge of the window when raised, comprising an elongated member of 70 resilient material adapted when mounted in position to extend a substantial distance below said seat and into contact with the window when raised to seal against influx of air and to prevent rattling, said member being substantially uniform 75

in cross section and being provided with a flexible sheet reinforcement for the downwardly extended portion and being cut away at its forward end to form a ventilating opening.

5 7. A ventilating strip adapted to be attached to the top frame member of the vehicle window provided at its lower edge with a projecting bead to contact with the window when raised, one portion of said strip being cut away whereby when 10 the window is lowered until its top edge is in contact with said projecting bead a ventilating opening will be provided through said cut-away portion.

10 8. A combined cushioning and ventilating device adapted to replace the conventional cushioning means employed in the channeled top frame member of window guideways for vehicles, comprising an elongated member of resilient material, 15 U-shaped in cross section, both legs of the U-shaped member extending a substantial distance below said top frame member when said device is inserted in the channel of the latter and being separated from each other at their lower edges by a space slightly less than the thickness of the 20 window glass, said edges being beveled to permit entry of the glass and being cut away at their forward ends to form a ventilating opening when the window is raised substantially to the lower edges of said legs.

25 9. A ventilating strip adapted to be attached to the top frame member of a vehicle window

with one of its lower horizontal edges in substantial contact with the window when raised, the base of said strip being provided with an adhesive composition covered by a removable protecting material, a portion of said strip being cut away whereby when the window is lowered until its top edge is in contact with the uncut bottom edge of said strip a ventilating opening will be provided through said cut-away portion.

5 10. A ventilating strip adapted to be attached to the top window frame member of a vehicle with one of its lower horizontal edges in substantial contact with the window when partially raised, one portion of said strip being cut away whereby when the window is lowered until its 15 top edge is in contact with the uncut bottom edge of said strip a ventilating opening will be provided through said cut-away portion.

10 11. A ventilating strip of flexible material adapted to be attached to the top window frame 20 member of a vehicle with one of its lower horizontal edges in substantial contact with the window when partially raised, one portion of said strip being cut away parallel to its base to form an elongated portion of less depth than the main 25 portion and capable of flexibly conforming to a downwardly curved seat under the top window frame member, said cutaway portion providing a ventilating opening.
